UNITED STATES PATENT OFFICE.

MOSES LEVINSON, OF NEW YORK, N. Y.

ELECTRIC IRON.

1,272,063.

Specification of Letters Patent.

Patented July 9, 1918.

Application filed November 2, 1917. Serial No. 199,866.

To all whom it may concern:

Be it known that I, Moses Levinson, a citizen of the United States of America, and a resident of the city, county, and State 5 of New York, have invented a new and useful Improvement in Electric Irons, which invention is fully set forth in the following specification.

The objects of this invention are to produce a neat, compact, comparatively small, yet highly efficient ironing-device,—as suitable for use in the boudoir or kitchenette as in the hall bedroom, especially for ironing out ladies' lingerie and other delicate 15 fabrics, etc., and which can be collapsed and put away in a small receptacle. The new iron, which I have termed the "Little Goose", is, in effect, an electric iron *de luxe*.

The present application is filed to take 20 the place of my earlier application, Serial No. 192,368, filed Sept. 20, 1917, in which were set forth and claimed the features covered by the generic claims of the present application.

25 Among the features of the invention are: locating the electric heating-device between the face-member (which transmits the heat directly to the article being ironed) and a heat-storing member which is insulated 30 from the back-member of the implement; providing a collapsible handle; providing a suitable recess within the contour of the iron for receiving the detachable electric-plug connection; and providing suitable 35 electric-insulation and heat-insulation.

Other features of the invention will be herein more fully set forth and claimed.

The invention is susceptible of expression 40 in various forms. One embodiment is set forth in the following description and the accompanying drawings, but merely as an illustrative example, it being understood that the invention itself is defined in the appended claims.

45 This preferred embodiment is shown in the annexed drawings, in which—

Figure 1 is a longitudinal vertical section through the various parts, shown as separated from one another, and somewhat exaggerated in thickness;

Fig. 2 is a side-view, with the handle part way collapsed;

Fig. 3 is a plan, on a smaller scale, with the handle removed and its connecting-links 55 shown in horizontal cross-section, showing

also the detachable plug slightly removed; and

Fig. 4 is a rear elevation.

In these drawings, 1 is the face-member, of the usual contour for flat-irons, and having a slight beading around its upper edge, and containing the two horizontal binding-posts 2. Upon the top of this member lies a sheet of heat-transmitting electric-insulation 3, of mica or the like. Upon this insulation 3 lies the electric heating-device, such as an elongated horse-shoe 4 of mica, having a ribbon 5 of resistance-material wound around it with its terminals secured to the two binding-posts. Upon this electric device lies another sheet of heat-transmitting electric-insulation 6. Upon this second sheet rests a heat-storing body 7, of metal, shaped to conform to the member 2, but of somewhat smaller contour; 75 and, in this particular embodiment, this member 7 is shown as having a central longitudinal slot, near each end of which is pivoted one of the two links 8—8 for the handle. Upon this member 7 lies a body 80 9 of heat-insulating electric-insulation, such as asbestos (with a similar longitudinal slot to provide clearance for the handle-links). Upon this member 9 lies the back-member or cover 10 (likewise provided with a longitudinal slot for the handle), and shown as having a flange extending down to the face-member 1. All the foregoing parts are suitably secured together, as by two screws 11, that pass through the back-member 10 and 90 are threaded into the face-member 1.

In the preferred form of collapsible handle, the handle 12 is tubular, with a longitudinal slot along its underside, and an apertured closure secured in each end. A 95 locking-shaft 13 is journaled in these apertures, with an external milled-head 14; and near the ends of this shaft are enlargements provided with oppositely-disposed open-ended locking-grooves (in the nature of 100 coarse feed-screws). The upper ends of the links 8 extend through the slot and into the hollow of the handle, where they are retained, as by a cross-head 15 (being inserted before the tube-closures are secured in 105 place). The extreme top of each link constitutes a locking-projection 16, adapted to enter the open end of the adjacent locking-groove. By rotating the milled-head 14 in one direction, the projections 16 are forced 110

outwardly and disengaged, whereupon the handle can be collapsed, the upper ends of the links sliding along the handle, toward each other (as indicated in Fig. 2), until 5 the handle is entirely collapsed. On raising the handle, it is secured in raised position by turning the milled-head 14 in the opposite direction while at the same time forcing the two links outwardly, so that said locking-projections 16—16 will enter and become engaged in their respective grooves. For convenience in raising the handle, there may be the two depressions 17—17 in the cover 10 and in members 9 and 7.

15 Preferably, although the rear end of the face-member may extend straight across, the other members are cut away in substantially a half circle (as indicated in Fig. 3), to receive the detachable plug 18; and the 20 binding-posts protrude into said cut-away space, somewhat like the after-deck guns of a ship; but, if desired, the face-member also might be similarly concaved at the rear. The usual flexible cable 19 is secured to the 25 detachable plug, which has two terminals to engage the two binding-posts. But any suitable form of plug and connections could be employed.

It will be understood that parts of the 30 invention can be employed to the exclusion of other parts, various parts transposed or inverted, and modifications made, without in any case departing from the spirit of the invention.

35 The invention having been thus fully set forth in detail, but only for the sake of clearness, what is claimed is:

1. An electric iron, comprising face and back members, a collapsible handle, and 40 suitable electric heating-devices located between said face and back members and electrically insulated therefrom.

2. As a new article of manufacture, an electric iron containing suitable electric 45 heating-means and provided with a recess within its contour for receiving a detachable electric plug, and a collapsible handle secured to said iron.

3. As a new article of manufacture, an

electric iron containing suitable electric 5 heating-means and provided with a recess within its contour for receiving a detachable plug, a collapsible handle secured to said iron, and means for maintaining said handle in raised position. 55

4. An electric iron containing suitable electric heating-means, a handle for said iron, two links pivoted to said iron and slidably connected to said handle, a shaft carried by said handle and having grooves for 60 engaging the upper ends of said links for securing said links upright to maintain said handle in raised position.

5. An electric iron containing suitable electric heating-means, two links foldably 65 pivoted to said iron, and a handle to which said links are slidably connected, whereby said handle may be collapsed to rest upon said iron.

6. An electric iron containing suitable 70 electric heating-means, two links foldably pivoted to said iron, a handle to which said links are slidably connected, whereby said handle may be folded down upon said iron, and means for maintaining said handle in 75 raised position.

7. An electric iron consisting of the combination of a face-member, a heat-storing member, an electrically-insulated electric 80 heating-device interposed between the two members, a back-member, a heat-insulator for the latter, and a collapsible handle.

8. An electric iron consisting of the combination of a face-member, a heat-storing member, an electrically-insulated electric 85 heating-device interposed between the two members, a back-member, a heat-insulator for the latter, a collapsible handle, and means for maintaining the handle in raised position. 90

In testimony whereof I have signed this specification in the presence of two subscribing witnesses.

MOSES LEVINSON.
